United States Patent Office.

DAVID C. FRAZEUR AND WILLIAM D. COCKLIN, OF SIDONSBURG,
PENNSYLVANIA.

Letters Patent No. 91,735, dated June 22, 1869.

IMPROVEMENT IN FARM-GATES.

The Schedule referred to in these Letters Patent and making part of the same.

To all whom it may concern:

Be it known that we, DAVID C. FRAZEUR and WILLIAM D. COCKLIN, of Sidonsburg, in the county of York, and State of Pennsylvania, have invented a new and valuable Improvement in Farm-Gates; and we do hereby declare that the following is a full, clear, and exact description of the construction and operation of the same, reference being had to the annexed drawings, making a part of this specification, and to the letters and figures of reference marked thereon.

Figure 1, of the drawings, is a front plan view of our invention.

Figures 2 and 3 are details.

Our invention relates to farm-gates; and

It consists mainly in a novel arrangement of devices by which the front end of such gates may be raised upward to any desirable altitude, while the rear ends remain in a fixed position.

The letters A and B, of the drawings, respectively represent the front and rear vertical slotted end-pieces of our gate, in which the rails are pivoted, as shown.

The letter C is the middle vertical slotted bar, in which the upper rail is pivoted, as shown.

The letters D are the rails, or slats of our gate.

The lower rail of our gate is perforated with pin-holes, as shown by letter s, which pin-holes correspond in size with pin-hole y, that passes through the bottom of the centre slotted gate-bar.

The letter n is the latch, pivoted in the slot of the centre bar, as shown.

When the gate is fixed in a horizontal position, as shown by the black lines on fig 1, a suitable pin is passed through the pin-holes y and s, and holds the gate firmly in that position; but when we desire to elevate the front end of the gate, we remove said pin, and raise the front end upward until it assumes the position indicated by the red lines on said figure.

This arrangement serves the purpose of barring large animals from a field while small ones are admitted, and is valuable for a variety of purposes.

What we claim as our invention, and desire to secure by Letters Patent, is—

The arrangement, herein shown and described, of the rails D, the upper rail only being pivoted in the central gate-bar, and the lower rail having pin-holes s adapted to the pin-hole y and pin, as described, when constructed and operating substantially as and for the purposes specified.

In testimony that we claim the above, we have hereunto subscribed our names in the presence of two witnesses.

DAVID C. FRAZEUR.
WILLIAM D. COCKLIN.
